(No Model.)

A. L. WINGE.
WRENCH.

No. 527,643.

Patented Oct. 16, 1894.

UNITED STATES PATENT OFFICE.

ALF L. WINGE, OF MILES CITY, MONTANA, ASSIGNOR OF ONE-HALF TO
JOHN S. TRUSCOTT, OF SAME PLACE.

WRENCH.

SPECIFICATION forming part of Letters Patent No. 527,643, dated October 16, 1894.

Application filed December 22, 1893. Serial No. 494,480. (No model.)

To all whom it may concern:

Be it known that I, ALF LAUBERT WINGE, of Miles City, in the county of Custer and State of Montana, have invented a new and 5 Improved Wrench, of which the following is a full, clear, and exact description.

The object of the invention is to provide a new and improved wrench, which is simple and durable in construction, and arranged to 10 permit the operator to conveniently and quickly adjust the jaws and lock the same in position.

The invention consists of certain parts and details, and combinations of the same, as will 15 be fully described hereinafter and then pointed out in the claim.

Reference is to be had to the accompanying drawings, forming a part of this specification, in which similar letters of reference indicate 20 corresponding parts in all the figures.

Figure 1 is a side elevation of the improvement. Fig. 2 is an edge view of the same. Fig. 3 is a sectional side elevation with the end jaws open. Fig. 4 is a side elevation of 25 the end jaws arranged as a wire cutter. Fig. 5 is an edge view of the improvement with a handle substituted for the end jaws, the handle being in section. Fig. 6 is an enlarged sectional side elevation of the movable jaw. Fig. 7 is an enlarged sectional plan view of 30 the stock on the line 7—7 of Fig. 3; and Fig. 8 is a sectional plan view of part of the improvement on the line 8—8 of Fig. 4.

The improved wrench is provided with a stock A, carrying at its upper end the fixed jaw B provided at the back with downwardly extending prongs B' to form a claw hammer on the wrench. On the stock A is fitted to 35 slide a movable jaw C, carrying an interior plate formed with teeth D, adapted to mesh in correspondingly shaped teeth A', formed at one side of the stock A. The jaw C is provided with an upwardly projecting lug C', adapted to engage a corresponding recess in 40 the fixed jaw B. The purpose of this lug is to prevent the article clamped between the jaw from striking against and injuring the teeth A' of the stock. The opening in the 45 movable jaw C is sufficiently large to conveniently move the jaw C up or down on the

stock A, without engaging the teeth D with the teeth A'; but in order to lock the jaw C in place on the stock A with the teeth D meshing into the teeth A', I provide a wedge 55 E, adapted to pass into the opening of the jaw C, on the back of the stock A.

The inner face of the wedge E, is formed with a dovetail prong E' fitted to slide in a correspondingly shaped groove A², arranged 60 longitudinally in the back of the stock A. In order to lock the wedge E to the movable jaw C, I provide a spring catch F, fastened to the outer side of the wedge E, as is plainly shown in Fig. 6, the said catch being provided with 65 a projection F' adapted to engage a correspondingly shaped recess C', formed inside of the jaw C, so as to lock the said wedge in position in the jaw C.

The free end of the spring catch F, is provided with a finger piece F², extending outward through the head E² of the wedge E, as is plainly illustrated in Figs. 1, 3 and 6, so that the operator by pressing the finger piece F², can disengage the projection F' from the 75 recess C', to slide the wedge E out of the jaw C. When the wedge is in this position, the jaw C can be conveniently moved up or down on the stock A, to move the movable jaw C in engagement with the nut or other object 80 to be taken hold of by the wrench; it being understood that the said nut is also engaged on the one side by the fixed jaw B.

When the jaws B and C are in engagement with the opposite sides of the nut or other 85 article, then the operator pushes the wedge E along the back of the stock A to move it into the opening of the jaw C, so as to draw the latter to one side toward the back, to engage the teeth D with the teeth A', at the 90 same time causing the projection F' to snap into the recess C', thus locking all the parts in position.

The stock A, is preferably graduated to indicate linear measurement, as indicated in 95 Figs. 1 and 3. The outer end of the stock A, terminates in an edge A³ to form a screw driver on the said stock, the sides A⁴ and A⁵ of this outer end being curved, as is plainly shown in Figs. 1 and 3.

On the outer end of the stock A is arranged 100 a second gripping device G, comprising a

sleeve I, fitted to slide on the stock and adapted to be secured thereon by a set screw I'. On the sleeve I, are pivoted two jaws J and J', formed in their inner faces with 5 curved edges J² and J³, adapted to engage the curved sides A⁴ and A⁵, so as to move the jaws J and J' apart at their free ends at the time the sleeve I is shifted upward on the stock A.

- 10 In order to hold the jaws J and J' in position, I provide a ring K, through which extend the said jaws, and which also passes over the front and back of the stock A, as is plainly indicated in Figs. 1 and 3. This ring K is 15 adapted to be secured in place on the stock A, by a suitable pin L. Now it will be seen, that by loosening the set screw I', and moving the sleeve I upward on the stock A, the curved edges J² and J³ of the jaws J and J', 20 move up the similarly curved sides A⁴ and A⁵ of the stock A, so as to cause the jaws to swing apart, as is plainly illustrated in Fig. 3, whereby the outer ends of the said jaws are moved a distance apart, corresponding to 25 the article to be driven. When this distance between the outer ends of the jaws J and J' is reached, the sleeve I is fastened in place by the set screw I', and then the stock A is manipulated by the operator in the usual 30 manner, to turn the article gripped.
- On the jaw J, is secured a knife N, adapted to operate in conjunction with a fixed knife N', secured on the stock A, near the outer end thereof, as is plainly shown in Figs. 4 and 35 8, it being understood that the sleeve I is then locked in its normal lowermost position by the set screw I', and the ring K is entirely removed from the said jaws. Now it will be seen that by swinging the jaw J open, as 40 shown in Fig. 4, a wire, twine or other article

can be brought between the two knives N and N', and then by closing the jaw J, the wire, twine or other inserted article is cut by the cutting edges of the knives N and N', passing each other.

45

The gripping device G can be entirely dispensed with, as illustrated in Fig. 5, and a handle H substituted on the lower or outer end of the stock A. In this case the handle H is fastened in place on the stock, by the pin L, as will be readily understood by reference to the said Fig. 5.

It will be seen that the instrument above described, and shown in the drawings, can be conveniently used for various purposes, and 55 its several parts can be readily adjusted by the operator, and the parts locked in place after the article is gripped.

Having thus fully described my invention, I claim as new and desire to secure by Letters 60 Patent—

A wrench, comprising a toothed stock having a fixed jaw whose gripping surface extends essentially perpendicular to the longitudinal axis of the stock, a movable jaw embracing the stock and having longitudinal sliding movement thereon, the said movable jaw being provided with teeth adapted to mesh with those of the stock, a wedge fitted to slide between the movable jaw and the 70 stock, longitudinally of the latter, to lock the movable jaw to the stock, and a spring catch under the control of the operator, and secured to the said wedge, the said catch having a projection adapted to engage a recess in the 75 movable jaw, substantially as described.
